(57) **CLAIM**

The ornamental design for a container having rounded compartments, as shown and described.

DESCRIPTION

This application is related to the following co-pending applications filed concurrently herewith by the same Applicant: "Multi-Compartment Roll-Up Container" Ser. No. 14/621,542, "Multi-Compartment Roll-Up Container-Triangle", Ser. No. 29/517,510, and "Multi-Compartment Roll-Up Container-Rounded", Ser. No. 29/517,512. The complete disclosures of these co-pending applications are incorporated herein by reference.

FIG. 1 is a top perspective view of a container having rounded compartments, showing our new design;
FIG. 2 is a front elevation view thereof;
FIG. 3 is a rear elevation view thereof;
FIG. 4 is a left elevation view thereof;
FIG. 5 is a right elevation view thereof;
FIG. 6 is a top plan view thereof; and,
FIG. 7 is a bottom plan view thereof.

1 Claim, 6 Drawing Sheets
